UNITED STATES PATENT OFFICE.

OYSTEIN JACOBSEN, OF DAYTON, OHIO, ASSIGNOR TO THE DURIRON COMPANY, INC.,
A CORPORATION OF NEW YORK.

DOUBLE-ACTING PLUNGER PUMP.

Application filed July 23, 1924. Serial No. 727,674.

To all whom it may concern:

Be it known that I, OYSTEIN JACOBSEN, a citizen of the United States, and a resident of Dayton, in the county of Montgomery and State of Ohio, have made a new and useful invention in Improvements in a Double-Acting Plunger Pump, of which the following is a specification.

The invention relates to double acting plunger pumps and particularly to pumps for handling acid or other corrosive liquids, although the invention is not limited in its field of usefulness to the pumping of such liquids. It has for its primary objects; the provision of an improved construction in which provision is made for draining the liquid from the cylinder and from the packing grooves surrounding the plunger when the actuation of the plunger or piston is stopped; the provision of improved means for protecting the packing gland of the piston or plunger rod from contact with the corrosive fluid handled by the pump and for preventing any leaks at such gland; and the provision of improved and simplified inlet and discharge valve constructions for securing the desired double action in the pump. One embodiment of the invention is illustrated in the accompanying drawing, wherein:

Figure 1 is a partial vertical section through the pump and partial side elevation. Fig. 2 is a front elevation. Fig. 3 is a plan view. Figs. 4 to 7 are detail views of the cylinder casting, Fig. 4 being a side elevation with the lower portion broken away along the line IV-IV of Fig. 5, Fig. 5 being a section on the line V-V of Fig. 4, Fig. 6 being a side elevation, and Fig. 7 being a horizontal section on the line VII-VII of Fig. 4. Figs. 8 to 12 are enlarged detail views of the inlet or suction valve, Fig. 8 being a partial plan view and partial horizontal section on the line VIII-VIII of Fig. 9, Fig. 9 being a partial front elevation and partial vertical section on the line IX-IX of Fig. 10, Fig. 10 being a partial side elevation and partial vertical section on the line X-X of Fig. 9, and Fig. 11 being a plan view of the valve retainer. And Figs. 12 to 14 are enlarged detail views of the outlet or discharge valve, Fig. 12 being a partial plan view and partial horizontal section on the

line XII-XII of Fig. 13, Fig. 13 being a partial front elevation and partial vertical section on the line XIII-XIII of Fig. 14, and Fig. 14 being a partial side elevation and partial section on the line XIV-XIV of Fig. 13.

Referring to the general arrangement shown in Figs. 1, 2 and 3; 1 is the base casting, upon which the pump is carried, having a pair of pedestals 2, 2, in which is mounted the driven shaft 3, provided with the belt pulleys 4. A pair of cranks 5, 5 are mounted in a second of pair of pedestals 6, 6, the cranks being rotated from the shaft 3 by means of suitable reduction gearing in the casings 7, 7. The cranks are connected to a cross head 8 by means of the connecting rods 9, 9, to which is secured the upper end of the piston rod 10.

The piston rod is guided in the sleeve or collar 11 carried by the upper end of the standard 12, such standard being rigidly bolted to the base casting 1, as indicated in the drawings.

The pump proper is preferably made up of four castings bolted together and comprising, the cylinder casing 13 having the cavity or bore 14 in which the plunger 15 is mounted; the lower cylinder head 16 bolted to the base casting 1; the upper cylinder head 17; the inlet or suction valve 18; and the outlet or discharge valve 19.

Extending along one side of the cylinder casing are the pair of inlet passages 20 and 21 (see Fig. 4 in connection with Fig. 1), the passage 20 leading into the lower end of the cylinder cavity at 22, as indicated in Fig. 1, while the other passage 21 similarly leads into the upper end of the cylinder cavity at 23, as will be understood by reference to Figs. 4 and 7. These passages 20 and 21 each also have an outlet branch leading from the lower ends thereof into the casing 19, as indicated at 24, 24, and inlet openings 25, 25 at their upper ends leading from the casing 18 (Figs. 1 and 4).

The inlet or suction casing 18 and the valves therein are shown in Figs. 8 to 11. The interior of the casing is divided into two chambers or passages 26, 26 by the vertical wall 27, and such passages communicate through the openings 28, 28 with the open-

ings 25, 25 (Figs. 1 and 4), leading into the passages 20, 21. The chambers or passages 26, 26 communicate through openings 29, 29 with a chamber 30 therebeneath having the suction inlet 31. The openings 29, 29 are provided with the ball check valves 32, 32 limited in upward movement by the sleeves 33, 33. The top of the casing is closed by means of the cap 34.

10 The cap 34 has a drain passage 35 leading from the chamber 36 in the upper cylinder head 17, and the drainage from this passage 35 leads into the vertical cavity or passage 37 (Figs. 8 and 10), leading down 15 into the suction inlet. In this manner suction is always applied to the chamber 36 during the operation of the pump so that any leakage to the chamber is immediately conducted away without coming into contact with the gland 38. Leakage at this 20 gland is thus prevented, and the corrosive liquid, which the pump is designed to handle is prevented from coming into contact with the packing of the gland and destroying it.

25 The outlet or discharge casing 19 and the valves therein are shown in Figs. 12 to 14, the construction being very similar to that of the suction casing and valves as just described. A partition or wall 39 divides 30 one half of the casing into two chambers 40 and 41 which communicate through the openings 42 with the openings 24, 24 (Figs. 1 and 4) leading to the passages 20 and 21. The chambers 40 and 41 also communicate 35 through the openings 43 with the chamber 44 (Fig. 12), such openings being controlled by means of the check valves 45. An outlet passage 46 leads from the chamber 44. Packing grooves in the collar 47 tend to reduce the leakage into the chamber 36 at this 40 point.

In operation, as the plunger 15 moves upwardly, the liquid on the upper side flows through the opening 23 (Fig. 4 and 7) and into the passage 21, from which it is forced through one of the openings 24 into the outlet casing 18, past one of the check valves and through the outlet 46. At this time no liquid can be sucked from the discharge 50 casing through the other passages 24 leading into the passage 20 since the other check valve in the discharge casing prevents this.

Liquid is supplied to the lower side of the plunger 15 during this upward movement, 55 through the passage 20 (Fig. 1), such passage receiving its supply through one of the openings 25 leading into the suction or inlet casing 18. This liquid is supplied from the suction inlet 31 past one of the check valves 60 32. At this time no liquid can be forced into the casing 18 from the upper side of the plunger through the passage 21 and the other opening 25 leading into the casing 18, because of the other check valve 32.

65 On the reverse movement of the plunger,

the action in the inlet and discharge casings is reversed, the liquid from the lower side of the plunger flowing through the passage 20 and into the discharge casing and thence past the check valve which had previously 70 been closed, while liquid is drawn into the cylinder above the plunger through the passage 21, such liquid being supplied from the casing 18 past the check valve which had previously been closed.

In order to provide a packing for the plunger 15, the grooves 48 are employed in the wall of the plunger cavity or bar at its central portion, and as indicated in Figs. 4 and 5, the grooves are placed in communication with the passages 20 and 21 by means of the lateral passages 49. This provides for a supply of liquid to the packing grooves 48 during the operation of the pump and when this operation is concluded, the passages 49 permit the passages to drain as well as the part of the cylinder above the plunger. This is important where acid is the liquid pumped, as the removal of such acid is necessary in order to avoid sulphating the cylinder and piston surfaces. The liquid collecting in the bottom of the cylinder after the pump stops is drained out through a suitable outlet 50 (Fig. 2) provided with a suitable cut off cock or valve.

What I claim is:

1. In combination in a pump, a cylinder provided with a chamber at one end having inner and outer end walls, a plunger in the cylinder provided with a rod extending through the two end walls of said chamber, a packing gland in the outer one of said end walls around the rod, an inlet valve casing having a passage connected with the cylinder so that suction is applied to the passage during the movement of the plunger in one direction, and a drainage connection between said chamber and said passage.

2. In combination in a pump, a cylinder provided with a chamber at one end having inner and outer end walls, a plunger in the cylinder provided with a rod extending through the two end walls of said chamber, a packing gland in the outer one of said end walls around the rod, an inlet valve casing having a passage connected with the cylinder so that suction is applied to the passage during the movement of the plunger in one direction, and a drainage connection between said chamber and said passage, said inner wall being provided in its surface surrounding the rod with packing grooves.

3. In combination in a pump, a cylinder provided with a chamber at one end having inner and outer end walls, a plunger in the cylinder provided with a rod extending through the two end walls of said chamber, a packing gland in the outer one of said end walls around the rod, an inlet valve casing having a passage provided with a check

valve and connected with the cylinder so that the suction is applied to the passage during the movement of the plunger in one direction, and a drainage connection leading 5 from said chamber to said passage on the inlet side of said check valve, so that suction only is applied to said drainage connection.

4. In combination in a pump, a cylinder 10 casing having a circumferential packing groove on the inner surface of the plunger cavity or bore at its central portion, and having an inlet passage extending longitudinally of the casing at the side of such 15 cavity, and having a drain hole extending laterally through the wall of the casing from said groove to said passage, and a plunger mounted in said cavity or bore.

5. In combination in a pump, a cylinder 20 casing having a plurality of circumferential packing grooves on the inner surface of the plunger bore or cavity at its central portion and having an inlet passage extending longitudinally of the casing at the side of the 25 bore or cavity, and having a drain hole extending laterally from each of said grooves through the wall of the casing to said passage, and a plunger mounted in said cavity or bore.

6. In combination in a pump, a vertical 30 cylinder casing having a circumferential packing groove on the inner surface of the plunger cavity or bore at its central portion, and having an inlet passage extending longitudinally of the casing at the side of such 35 cavity or bore, and having a drain hole extending laterally through the wall of the

casing from said groove to said passage, and a plunger mounted in said cavity or bore.

7. In combination in a pump, a vertical 40 cylinder casing having a plurality of circular packing grooves on the inner surface of the plunger cavity or bore at its central portion, and having a pair of inlet and discharge passages extending longitudinally of 45 the casing at the side of such cavity or bore and communicating therewith at its ends, and a plunger mounted in the cavity or bore, a drain hole being provided through the 50 wall of the casing between each groove and each of said passages.

8. In combination in a pump, a cylinder 55 casing provided with a pair of inlet passages leading to the opposite ends of the cylinder cavity or bore, and each having an outlet or discharge branch, an inlet valve casing having a pair of passages provided with check valves communicating with said inlet passages and themselves having a common inlet, an outlet valve casing having a pair of 60 passages provided with check valves communicating with said outlet discharge branches and themselves having a common outlet, and a plunger mounted in said cavity or bore, the cylinder wall being provided 65 on its inner surface at its central portion with a packing groove having communication through the cylinder wall with said inlet passages.

In testimony whereof, I have hereunto 70 subscribed my name this 21st day of July, 1924.

O. JACOBSEN.
